Primary Examiner — Elizabeth J Oswecki(74) Attorney, Agent, or Firm — Dunlap Bennett & Ludwig, PLLC(57) CLAIM

The ornamental design for a heel, as shown and described.

DESCRIPTION

FIG. 1 is a perspective view of a heel, showing my new design;

FIG. 2 is another perspective view of FIG. 1, shown in a used condition with a human foot in broken lines;

FIG. 3 is a lateral side elevation view of FIG. 1;

FIG. 4 is a medial side elevation view of FIG. 1;

FIG. 5 is a front elevation view of FIG. 1;

FIG. 6 is a rear elevation view of FIG. 1;

FIG. 7 is a top plan view of FIG. 1; and,

FIG. 8 is a bottom plan view of FIG. 1.

The broken lines in the drawings showing a human foot and shoe illustrate environment and form no part of the claim.

1 Claim, 4 Drawing Sheets(56)
